UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

PASTING DEVICE FOR WEB PRESSES.

Original application filed April 9, 1915, Serial No. 20,348. Patent No. 1,378,304. Divided and this application filed April 26, 1921, Serial No. 464,577. Renewed December 16, 1925.

This is a division of my patent No. 1,378,304, granted May 17, 1921, on an application filed April 9, 1915, and the invention relates to a pasting device for use in connection with a web press.

The principal objects of the invention are to provide means for applying a continuous supply of paste along a margin of the web while the press is running; to provide simplified means whereby the paste can be forced on the web by pneumatic pressure, and means whereby the paste receptacle can readily be applied to the press and removed therefrom without having to stop the press. 10 The invention also involves improvements in the mechanism for accomplishing these results.

Reference is to be had to the accompanying drawings, in which—

20 Fig. 1 is a section of a preferred nozzle in accordance with this invention as applied to a web press;

Fig. 2 is a plan of the nozzle, and

25 Fig. 3 is a perspective view of the pasting device.

This invention is designed to obviate the difficulties mentioned in my above mentioned patent and especially to permit of the running of the press at a high rate of speed 30 without danger of throwing off any paste.

Although the details of the press are not illustrated herein, yet the device is intended for use on a web press. This press constitutes the means for feeding the web referred 35 to herein. On the frame of this press is shown a pair of brackets for supporting a tray 48 carrying a pair of paste receptacles or containers 43.

40 Each container is kept in air-tight condition on the top. Through the cover passes a paste tube 42. It is open at the bottom and is provided with a coupling 44 for detachably connecting it to a branch pipe 41. These two pipes are connected to a horizontal 45 tube 40 provided with an upwardly opening nozzle. This has a horizontal flat surface 19 at the top, parallel with the direction of the web W, and substantially in contact therewith. This surface is provided 50 with a perforation 20, preferably substantially at the center thereof. This perforation is made small to permit of the paste being forced through to form a small thread or stream, as will appear. From this

perforation a shallow channel 21 extends to 55 the edge of the surface 19, running in the same direction as the web and slanting upwardly toward the edge of this surface. This is provided for the purpose of smoothing out and thinning the strip of paste applied to the web.

The pipe sections 41 immediately above these couplings 44 are provided with ball checks 45 to prevent leakage of paste when the cans are removed. These cans are connected with the air pipe line 46 by sections of hose 47 or the like, detachably connected with the cans. The cans are shown as supported on a tray 48 and the tube 40 as being carried by a suitable brace 49 on the 60 frame of the press.

The operation of the device is as follows: Upon the pressing of the starting button 30, air under pressure is admitted to the paste receptacle in the way shown in my above 65 mentioned patent, if desired. At this time, of course, the press starts and the paste is forced through the nozzle opening 20 against the surface of the web W as the latter travels. The passage of the paste along the 70 channel 21 spreads it and smooths it so as to get a line of paste on the web, of uniform width and thickness. The pressing of the stopping button 31 will relieve the interior 75 of the container of the air pressure and stop the flow of paste immediately. Thus the paste will not be blown out when no web is running, as in case of a paper break, or when the web is being threaded in the press.

80 The especial advantage of this construction is the simplicity and the means whereby a continuous supply of paste can be furnished while the machine is running, without having to stop the press if one of the cans has to be removed. When this is done, 85 the stop cock 50 connected to that can is shut, that hose 47 disconnected from the can, and the coupling 44 on that side opened. The check valve immediately closes this connection and the paste continues to flow from 90 the other can.

95 Although I have illustrated and described only one embodiment of the invention, I am aware of the fact that many modifications can be made therein by any person skilled in the art without departing from the scope of the invention as expressed in the claims. Therefore I do not wish to be limited to the 100 105

details of construction herein shown and described, but what I do claim is:-

1. In a pasting device for a web, the combination with means for moving the web along a path, a closed paste receptacle having a nozzle for applying paste against the surface of the web as it moves, means for applying pneumatic pressure to the paste in the receptacle for forcing the paste under pressure through the nozzle, means for starting and stopping the introduction of air into the receptacle to control the flow of the paste and means for supplying paste to the nozzle from another source when said receptacle is not in operation.
2. In a pasting device, the combination of a plurality of paste containers, a nozzle connected with all the containers for directing paste therefrom against a traveling web, a pipe system for taking the paste from all of the containers to the nozzle, an air supply pipe entirely disconnected from said pipe

system, and means connected with said air supply pipe and with said containers for forcing air into them to force the paste, unmixed with air, into said pipe system.

3. In a pasting device, the combination of a plurality of paste containers, a nozzle connected with all the containers for directing paste therefrom against a traveling web, a pipe system having automatically closing valves therein for taking the paste from all of the containers to the nozzle, an air supply pipe, and means connected with said air supply pipe and detachably connected with said containers for forcing air into them behind the paste therein, whereby any of said containers can be detached and the remaining ones will continue to supply paste to the nozzle.

In testimony whereof I have hereunto affixed my signature:

HENRY A. WISE WOOD.
